UNITED STATES PATENT OFFICE.

ROBERT WILLIAM KING, OF TORONTO, CANADA.

BUILDING CONSTRUCTION.

SPECIFICATION forming part of Letters Patent No. 684,438, dated October 15, 1901.

Application filed February 18, 1901. Serial No. 47,724. (No model.)

To all whom it may concern:

Be it known that I, ROBERT WILLIAM KING, a subject of the King of Great Britain, residing at Toronto, in the Province of Ontario, 5 Canada, have invented an Improvement in Building Construction, of which the following description, in connection with the accompanying drawings, is a specification, like numerals on the drawings representing like parts.

10 This invention relates to building construction which is especially adapted for greenhouses and similar structures; and its object is to provide a construction which will include means for collecting the moisture or water of 15 condensation which gathers on the inside of the roof of the building. The construction also involves means for conducting such moisture or water of condensation after it has been collected through the supports for the roof and 20 into a suitable drain, which will carry the same outside of the building.

In a greenhouse or other building where the moisture in the air condenses and collects upon the inside walls thereof constructed in 25 accordance with my invention the annoyance due to the inside drip is entirely obviated.

In constructing my greenhouse to accomplish the above-named object I provide suitable hollow arch-supports for the roof, upon 30 which are mounted troughs or other open conduits, situated directly underneath the lower portions of the slopes or the valley of the roof, so that any water of condensation which gathers upon the roof and runs down the same 35 will be collected in the open conduits or troughs and be conducted by them to the hollow supports, the said water passing through the supports and into the drain. The hollow arch-supports for the roof comprise what I 40 term "arch-heads," which are supported at each end by tubular standards or legs, said standards being connected to the drain. The arch-heads have suitably supported thereon beams which run lengthwise of the roof at the 45 valley of the roof, where the adjacent spans of the roof meet, and said beams have secured to either side thereof suitable brackets in which the lower ends of the sash-bars of the roof are supported. Immediately underneath 50 the beams, at either side thereof and supported on the arch-heads, are the troughs above mentioned, which empty into the hollow arch-

heads. The brackets which support the ends of the sash-bars are formed with a drip-groove surrounding the same, the mouth of the drip-groove being immediately over the trough, so that any water which runs down the sash-bars will be collected in said grooves and deposited into the trough.

A greenhouse embodying my invention will 60 be free from the annoyance due to the continual dripping of the water of condensation which collects on the inside of the roof thereof or that may leak through the joints of the glass.

In the drawings, Figure 1 is a section on the line 1 1, Fig. 2 is a section on the line 2, Fig. 1. Fig. 3 is a section on the line 3, Fig. 1. Fig. 4 is a section of the sash-supporting bracket on the line 4, Fig. 5. Fig. 5 70 is an elevation of such bracket, and Fig. 6 is a section of the sash-bar.

Greenhouse-roofs are usually made with a series of parallel roof-arches, which generally run longitudinally of the building, each roof-arch comprising the usual sash-bars, to which the glass is attached, the sash-bars serving as rafters and having their lower ends attached to and supported by beams, which beams are carried by suitable supports. When the roof 80 comprises a series of parallel roof-arches, the meeting edges of adjacent arches are supported on a beam which extends along the valley of the roof and is common to both arches, and in Fig. 2 are illustrated the meeting portions of two such adjacent roof arches or spans. Since the number of arches in any one roof depends on the size of the greenhouse and since each arch is of the same structure, it is not deemed necessary to further illustrate the invention. Each roof-arch 85 comprises the usual sash-bars 22, which support the glass in any ordinary way, the said sash-bars being supported at their lower ends by the beams 8, which beams are common to 90 two adjacent arches and run, preferably, lengthwise of the building along the valley of the roof. The means for supporting lower end sash-bars will be hereinafter described. The beams 8 are supported on suitable arch-supports comprising what I term "arch-heads" 95 3 and standards or legs 4 for supporting each end thereof, the said arch-heads being in the nature of cross-girders, which lie

at right angles to the beams 8 and are centrally positioned under said beams, as seen in Fig. 2. Each arch-head is hollow, as herein-after described, and the standards or legs 4 5 are also hollow, they preferably being tubular and being supported in arch-feet 5, which rest on suitable foundations, the said arch-feet being connected by pipe 6 to a drain 7. The arch-supports thus described form the 10 support for the roof-trusses, and, as seen in Figs. 1 and 2, the said arch-heads or cross-girders are made slightly arching and of channel-iron, so that they are substantially U shape in cross-section, and to strengthen the 15 same I preferably provide the under side of each arch-head with the web 3'. As illustrated, each arch-head carries the chair 9, shown as inverted-U shape, the lower portions thereof having the notches 10, which set into 20 suitable notches 11 in the top of the side portions of the U-shaped arch-heads, as plainly seen in Figs. 1 and 2. The top of the chair 9 is provided with a countersink, in which the head of a bolt 12 rests, the said bolt passing 25 down through the bottom of the U-shaped arch-head 3 and serving to secure the chair firmly in place. Each end of the chair is provided with a suitable aperture 13, through which lugs 14 upon the "beam ends" 15 project, the said beam ends having secured to 30 them in any suitable way the beams 8. To prevent the beam ends from becoming disengaged from the chairs, I may, if desired, pass suitable pins 16 through the lower ends of the 35 lugs, as seen in Fig. 1.

With this construction it will be seen that the beams 8 and their attached beam ends serve to tie together the various arch-heads, and in order to strengthen the beam I truss 40 the same by attaching thereto the posts 18, having open sockets at their lower ends, in which the truss-rod 19 is seated, the said truss-rod being fastened at its ends in any suitable way to lugs or ears 20 upon the beam ends. 45 The beams 8, it will be understood, support the lower end of the sash-bars 22, the said sash-bars serving as a support for the usual glass roof. I have devised special fittings or brackets 40 (illustrated in detail in Figs. 4 50 and 5) for thus securing the lower ends of the sash-bars to the beam 8, such brackets or castings having the side flanges 23 provided with the vertical edge 25' and the base 24, which is inclined, as illustrated in Fig. 4, the 55 upper edge of said base meeting the sides of the beam 8 at a point intermediate to the upper and lower edges thereof, as seen in Fig. 2, by reason of which construction the ends of the sash-bars rest partially against the 60 base 24 and partially against the sides of the beam 8, it being understood that the ends of each sash-bar are beveled to fit the angle between the base 24 of the fitting or bracket and the side of the beam 8, the ends of the sash-bars being secured to the brackets by suitable screws 51. The side flanges 23 have integral therewith the perforated ears or lugs 65

25, by means of which the said brackets or castings are secured to the sides of the beams 8, and the lower portion of each of said brackets has the upwardly-inclined flange 27 projecting therefrom on three sides thereof, the said flange forming a drip-groove for the purpose of collecting any water of condensation which runs down the sash-bars. Each 70 sash-bar is preferably provided with a drip-groove 48, running longitudinally along each side thereof, and the side flanges 23 are provided with the cut-away portion 49, which is in line with the drip-groove 48, whereby any 75 water which runs down said drip-groove 48 can flow through the cut-away portion 49 of the side flanges and into the drip-groove surrounding the bracket 40. Underneath either 80 side of the beam 8 and seated in suitable recesses in the top of the side pieces of the arch-heads 3 are troughs or open conduits 30, which empty into the U-shaped arch-heads, as 85 plainly seen in Fig. 1.

With this construction it will be obvious 90 that any water of condensation which collects on the glass or the sash-bars and runs down the same to the bottom of the slope of the roof will drip off into the troughs 30 and be conducted to the hollow arch-heads and 95 through the standards 4 to the drains 7, the water which runs down the sash-bars being collected by the drip-groove 27 in the brackets 40 and being deposited into the troughs. It will be noted in this connection that the 100 drip-groove which surrounds the bracket 40 is constructed on a slight inclination, as seen in Fig. 4, so that the water will freely pass out of the mouth thereof into the trough 30. 105

Referring to Fig. 3, it will be seen that the 110 posts 18 are provided on opposite sides with lugs 43, upon which the troughs 30 rest intermediate to their ends, the inside of said troughs being bolted to the posts by bolts 44. As seen in Fig. 4, the lower end of the vertical edge 25' of the flanges 23 is provided 115 with the notch 31, this notch being of the proper depth to receive the deflecting-plate 33, which is clamped between the fitting 40 and the beam, the lower edge of the plate extending below the under side of the beam 8 and said plate serving to positively direct the water which runs down the glass of the roof into the trough 30 and prevent the same from flowing around underneath the beam 8. 120

In order to strengthen the roof-trusses, certain of the sash-bars may be trussed, as seen at the right in Fig. 2, in which case the corresponding bracket 40 will have the lug 36 depending from the outer side thereof, the 125 said lug serving to sustain the truss-rod 37, which passes over a king-post 38, secured to the purlin 50, and is secured at its other end to the roof-ridge in any suitable way. (Not shown.) The arch-heads at either side of any roof-arch may be tied together by suitable tie-rods 39, which are connected to the bolt 12 at their ends in any suitable way, the 130 said tie-rods preferably having a suitable

turnbuckle 41 therein for the purpose of keeping the structure taut. A roof made as above described is exceedingly strong and durable and at the same time can be easily set up or taken down should occasion require, and, furthermore, provision is made for the collecting and conducting to the outside of the building through the hollow supports for the roof of any water of condensation which accumulates on the inside of the roof.

It will be understood that various changes may be made in the structure of my device without departing from the spirit of my invention, and I therefore reserve the right to make such changes as come within the appended claims.

Having described my invention, what I claim as new, and desire to secure by Letters Patent, is—

1. In building construction, a roof, a series of hollow supports therefor, said supports being connected to a suitable drain, and means to conduct any moisture which collects on the inside of the roof through said hollow supports to the drain.

2. In building construction, a roof, a series of hollow supports therefor, said supports being connected to a suitable drain, a trough or open conduit sustained by said supports and emptying into the same, said trough being situated at the bottom of the slopes of the roof, whereby moisture which collects on the inside of said roof will be conducted through said troughs and hollow supports to the drain.

3. In building construction, a series of hollow arch-heads, roof-trusses supported thereon, and means for conducting the water of condensation which collects on the inside of the roof through the hollow arched heads and to a drain.

4. In building construction, a roof, a series of hollow arch-heads supporting the same, tubular standards for the arch-heads, said tubular standards being connected to a suitable drain, and a series of troughs situated at the bottom of the slopes of the roof and emptying into said hollow arch-heads, whereby any moisture that collects on the inside of the roof is deposited into the troughs and conducted through the supports to the drain.

5. In building construction, a series of hollow supports, beams carried thereby, a roof supported on said beams, means to conduct any moisture which gathers on the inside of said roof to said hollow supports, and means to conduct said moisture from the hollow supports to the outside of the building.

6. In building construction for greenhouses, a series of hollow supports which are connected to a suitable drain, beams supported thereby, sash-bars connected at their lower ends to said beams, said sash-bars with the glass attached thereto forming the roof, and troughs underneath said beams and emptying into the hollow supports, whereby any moisture which collects on the inside of the roof

is conducted through the troughs into the hollow supports.

7. In building construction, a series of arch-heads, U shape in cross-section, hollow standards supporting the same, beams carried by said arch-heads and supporting the roof, and troughs mounted on said arch-heads and emptying into the same, said troughs being situated underneath said beams, whereby the moisture which is collected on the inside of the roof will be caught by said troughs and conducted through the arch-heads.

8. In building construction for greenhouses, a series of hollow arch-supports, which are connected to a suitable drain, beams carried thereby, brackets secured to said beams and adapted to support the lower ends of the sash-bars, said brackets having a drip-groove extending around the same, and a trough carried by and emptying into said arch-supports and situated beneath said beam, whereby any moisture which collects on the inside of the roof will be caught in said trough, the moisture which runs down the sash-bars being directed by the drip-groove in the brackets into the trough.

9. In building construction for greenhouses, a series of hollow arch-supports, which are connected to a suitable drain, beams carried thereby and supporting the meeting edges of adjacent roof-arches, brackets attached to both sides of said beams, said brackets having a drip-groove extending around the same, and side flanges provided with a cut-away portion, sash-bars supported at their lower ends in said brackets, and between said side flanges, said sash-bars having a drip-groove which registers with the cut-away portion of the side flanges, whereby the water which runs down the drip-grooves in the sash-bars is caught by the drip-grooves in the brackets, and means to conduct said water discharged by said drip-grooves in the brackets to the hollow arch-supports.

10. In building construction for greenhouses, a series of hollow arch-supports which are connected to a suitable drain, beams carried by said arch-supports, brackets attached to the said beams, said brackets having a drip-groove surrounding the same, sash-bars supported at their lower ends in said brackets, deflecting-plates secured between the brackets and beam, and troughs supported on and emptying into said arch-supports whereby any water that runs down the inside of the roof will be deflected by said plates into the troughs and emptied into the hollow arch-supports.

11. In building construction for greenhouses, a series of hollow arch-supports, beams carried thereby, brackets connected to said beams, said brackets having a drip-groove extending around the same, sash-bars supported at their lower ends in said brackets, and troughs situated underneath said brackets and emptying into the said hollow

arch-supports, certain of said brackets having a lug depending therefrom, and the corresponding sash-bars being trussed and having the truss-rod secured to said lug.

5 12. In building construction, a series of hollow arch-supports, chairs supported thereon and extending across the same, beam ends secured to said chairs, and beams secured to said beam ends and tying together the adjacent arch-supports, and a roof supported on said beams.

13. In building construction for greenhouses, a roof and supports therefor, said roof comprising a series of sash-bars serving as rafters, and glass suitably supported on said sash-bars, and a separate bracket for supporting the lower end of each sash-bar, said brackets each having a drip-groove partially surrounding the same, and means to catch the water delivered from the drip-grooves.

14. A supporting-bracket for sash-bars in greenhouse-roofs, said bracket having an inclined base or body portion of a size to fit and adapted to support the end of a sash-bar, and a drip-groove extending around three sides of said base or body portion, whereby any moisture which runs down the sash-bar is collected by the drip-groove.

15. A supporting-bracket for sash-bars in greenhouse-roofs, said bracket having an inclined base or body portion adapted to support the end of a sash-bar, parallel side flanges

either side of said base or body portion, each side flange having a cut-away portion, and a drip-groove partially surrounding the base. 35

16. A supporting-bracket for sash-bars in greenhouse-roofs, said bracket having an inclined base or body portion, parallel side flanges either side thereof, each side flange having a cut-away portion, a drip-groove partially surrounding the base or body portion, ears extending from said side flanges for attaching the bracket to a beam or other support, and a perforated lug at the base of the body portion adapted to receive a truss-rod. 45

17. In a building construction for greenhouses, a roof comprising the usual sash-bars, supports for the roof, said supports including a beam and a series of brackets detachably supported on the sides thereof, said brackets being adapted to receive the ends of the sash-bars, and each bracket having a drip-groove partially surrounding the same, combined with means situated underneath the beam for catching the water delivered from the drip-grooves. 50

In testimony whereof I have signed my name to this specification in the presence of two subscribing witnesses.

ROBERT WILLIAM KING.
